UNITED STATES PATENT OFFICE

DONALD F. HLADKY AND JOSEPH F. HLADKY, JR., OF CEDAR RAPIDS, IOWA

DESIGN FOR A VENDING MACHINE CASING

Application filed November 14, 1932. Serial No. 46,072. Term of patent 14 years.

To all whom it may concern:

Be it known that we, DONALD F. HLADKY and JOSEPH F. HLADKY, Jr., citizens of the United States, residing at Cedar Rapids, in the county of Linn and State of Iowa, have invented a new, original, and ornamental Design for a Vending Machine Casing, of which the following is a specification, reference being had to the accompanying drawing, forming a part thereof.

The figure is a perspective view of the vending machine, showing our new design, having regular and irregular shaped facets forming the exterior surfaces of the metal base and the glass bowl supply.

We claim:

The ornamental design for a vending machine casing, as shown and described.

DONALD F. HLADKY.
